UNITED STATES PATENT OFFICE.

JAMES HAYTON, OF SALT LAKE CITY, UTAH.

REVOLVING PLANE.

1,006,846.

Specification of Letters Patent. Patented Oct. 24, 1911.

Application filed September 29, 1910. Serial No. 584,432.

To all whom it may concern:

Be it known that I, JAMES HAYTON, a citizen of the United States, and a resident of Salt Lake City, in the county of Salt Lake and State of Utah, have invented new and Improved Revolving Planes, of which the following is a full, clear, and exact description.

This invention relates to revolving planes for flying machines, to take the place of the stationary planes now used therein.

An object of this invention is to provide a device which will be simple in construction, inexpensive to manufacture, strong, durable, easily controlled, and having a great supporting efficiency. This and further objects, together with the construction and combination of parts, will be more fully described hereinafter and particularly set forth in the claims.

Reference is to be had to the accompanying drawings forming a part of this specification, in which similar characters of reference indicate corresponding parts in all the views, and in which—

Figure 1 is a top plan view; Fig. 2 is a side view in elevation; and Fig. 3 is a detail bottom plan view of one of the revolving planes.

Referring more particularly to the separate parts of the device, it will be seen that I provide a pair of revolving planes 1 on each side of the flying machine. Each pair of revolving planes is secured to a shaft 2, supported anti-frictionally on a frame 3 by means of ball bearings 4. These revolving planes are to take the place of the stationary planes now used on biplanes and other types of flying machine, and have the advantage that, when stationary, they can be extended parallel to each other, so as to occupy one-half of the space now occupied by biplanes having the same supporting efficiency. The revolving planes occupy an area of at least one-half the total area of the circle through which they revolve, and have but a slight pitch.

The material of which the supporting planes are constructed may be of any suitable character, such as light, tough wooden blades secured to a central hub 5, through which the shafts 2 extend, by means of central disks 6 of any suitable light metal. The central hub, disk and blades may be cast of aluminum of one piece, if desired. The outer edges of the planes are reinforced by

means of metallic rims 7, which strengthen the planes and add to their rim force, giving greater steadiness of rotation.

The strain incident to supporting the flying machine is taken up in the plane by means of guy wires 8, which are secured to pins 9 on the disk 6, and extend to the corners and center of each plate, where they are secured in any well known manner.

The source of motive force for the revolving planes may be of any suitable character, such as a gasoline engine 10, which drives a pair of shafts 11 by means of chain-and-sprocket connections 12 and 13. These shafts 11 may be connected in driving relation with the shafts 2 by means of intermeshing bevel gears 14 and 15, located respectively on the shafts 11 and 2. The shafts 11 may be also utilized as propeller shafts, and are provided with propellers 16, which are adapted to drive the machine forward.

The flying machine is preferably supported on wheels 17, so as to permit it to run along the ground. The rising of the flying machine in the air can be controlled by a tilting plane 18, which is operated by a suitable lever 19, and connected thereto in any suitable manner, as by means of an arm 20 and a link 21. The lever 19 may be locked in any adjusted position by means of a latch mechanism 22, which engages a sector rack 23. A trailing plane 24 may be provided if desired, to add to the supporting surface of the flying machine.

The operation of the device will be readily understood when taken in connection with the above description.

The pairs of revolving planes on the machine are rotated by the engine 10, so that the pair on one side will revolve in the opposite direction to the pair of planes on the other side. By reason of the revolving planes being anti-frictionally connected with the frame by means of the ball bearings, they will revolve at a high speed with little or no friction. If, during the flight in the air, the engine should become disabled, the weight of the machine falling causes the planes to revolve, and keeps the machine in a perfect balance while descending to the ground, and even retards its speed of falling.

When the flying machine is at rest, with the revolving planes at rest, the pairs of planes on opposite sides of the machine will extend parallel to each other, so that they

occupy less space than is the case with the stationary planes on most flying machines.

It will thus be seen that I have provided revolving planes for flying machines, which will permit a more perfect supporting surface, taking up less space and having a higher factor of safety than the stationary supporting planes now in use in ordinary flying machines.

10 While I have shown one embodiment of my invention, I do not wish to be limited to the specific details thereof, but desire to be protected in various changes, modifications and alterations which may come within 15 the scope of the appended claims.

Having thus described my invention, I claim as new and desire to secure by Letters Patent:

1. A flying machine having a pair of revolving planes on each side thereof, said planes comprising a hub, blades, disks for securing said blades to said hub, said blades having a slight pitch, reinforcing metallic strips located on the outer rims of said 25 blades, and guy wires for transferring the strain on said blades, connected to said disk and to the corners and centers of said blades.

2. A flying machine having a pair of revolving planes mounted on each side thereof,

the top plane of each pair being superposed 30 directly above the bottom plane, said planes each comprising a hub, blades, disks for securing said blades to said hub, said blades having a slight pitch and extending in circular spaced relation from each other, and 35 reinforcing metallic strips located on the outer rim of said blades.

3. A flying machine, comprising a frame, a vertical shaft at each side of the frame and extending above and below the frame, a 40 pair of planes on each shaft, one on the upper end of the shaft and the other on the lower end thereof, each plane consisting of two oppositely projecting blades, a horizontal shaft geared at one end with each 45 vertical shaft, a propeller on the other end of each horizontal shaft, a motor, and means for operating the horizontal shafts in different directions from the motor, whereby the planes on one side will revolve in an 50 opposite direction to those on the other side.

In testimony whereof I have signed my name to this specification in the presence of two subscribing witnesses.

JAMES HAYTON.
